PULLING DIE

Abraham Solosko, Chicago, Ill.

Application May 1, 1936, Serial No. 77,353

5 Claims. (Cl. 223—25)

This invention relates to pulling dies for hats.

One form of the invention is shown as applied to a device of this character wherein a crown portion is associated with a base portion which is so formed as to provide a surface to receive the brim of a hat.

The present invention concerns itself more specifically with means for adjusting the relative height of the crown portion so that the operator may readily elevate the crown portion to any desired height with respect to the base portion and lock it in its elevated position.

The features and advantages of the invention will appear more clearly from the following description, reference being had to the accompanying drawings wherein a preferred form of the invention is shown.

In the drawings—

Fig. 1 is a view in side elevation of a pulling die embodying the invention;

Fig. 2 is a horizontal sectional view taken on the line 2—2 of Fig. 1;

Fig. 3 is a vertical sectional view taken on the line 3—3 of Fig. 2; and

Fig. 4 is a fragmentary sectional view taken on the line 4—4 of Fig. 3.

Referring now in detail to the drawings, the pulling die, as shown, comprises a stand portion 5 which is cast of a suitable material. The stand portion 5 is of a substantially oval shape in horizontal cross section and decreases in size upwardly as shown most clearly by Fig. 3. A plurality of downwardly extending portions 6 of the casting 5 provide legs for supporting the device on a bench or work table. A crown portion 7, comprising a hollow dome shaped casting, is formed to fit within an opening 8 of the stand 5. In order that the crown portion 7 may fit closely to the upper edge 9 of the stand 5, the outer surface of the open end of the crown portion is extended vertically without decreasing in size for a substantial distance. The upper part of the crown portion 7 may take any desired shape such as the irregular shape shown in Fig. 3 at 10 for giving a desired shape to the hat. Immediately below its top edge 8, the stand 5 is provided with an outwardly flaring surface 11 which is utilized to receive the brim of a hat stretched over the crown 7, as will be readily understood.

The crown 7 is vertically adjustable within the stand 5. A bar 12 has a head 13 thereon which is secured to the crown 7 by means of screws 14 to depend from the crown down into the hollow space 8 within the stand 5. The bar 12 has thereon a series of gear teeth 15 which mesh with

a gear 16 rotatably mounted in the stand 5 for raising and lowering the crown. The stand 5 has cast therein a web 17 which extends across the stand 5 and is provided with a vertically extending bearing 18 for the bar 12. This vertically extending bearing 18 is offset horizontally from portions 19 and 20 of the web 17 and is slotted with a slot 21 to receive the bar 12. The bar 12 is substantially cylindrical except for the provision of the gear teeth 15 which project from the bar and are narrower in width than the diameter of the bar 12. The slot 21 has a cylindrical portion which receives the cylindrical part of the bar 12, and has a reduced straight portion 22 in which the teeth 15 are vertically movable. The bearing 18 is hollowed out at 23 to provide space for the gear 16 and a hub 24 for the gear 16. The portion 20 of the web 17 and a part of the portion 19 of the web 17 are drilled to provide a cylindrical hole 25 to receive a shaft 26 on which the gear 16 is secured by means of a set screw 27 in the hub 24 of the gear. A washer 28 may desirably be interposed between the hub 24 and the adjacent part of the web 17. The shaft 26 carries a hand wheel 29 for rotating the gear 16 to raise and lower the bar 12.

In order to lock the bar 12 and the crown 7 in any desired position, the bearing 18 is provided with a screw threaded opening 30 which extends into the cylindrical part 21 of the slot 21 which receives the bar 12. A screw threaded rod 31 extends through the stand 5 and is screw threaded into the opening 30 to engage against the bar 12 and lock it in any position. A wing nut 32 is provided on the outer end of the rod 31.

The operation of the device is believed to be readily apparent from the foregoing description. It is also believed to be evident that the crown 7 may be readily removed from the stand 5 by releasing the rod 31 and lifting the crown to remove the bar 12 from the bearing 18. Thus any desired shape of crown may be used with the stand 5 so long as it fits the opening provided in the top of the stand. Different crowns 7 may be interchanged with stands having different shaped brim receiving surfaces 11 to provide any desired combination of crown and brim shape.

While certain embodiments of the invention have been shown and described, it is to be understood that it is capable of many modifications. Changes, therefore, in the construction and arrangement may be made without departing from the spirit and scope of the invention as disclosed in the appended claims in which it is the intention to claim all novelty inherent in the invention.

tion as broadly as possible in view of the prior art.

Having thus described the invention, what I claim as new and desire to secure by Letters 5 Patent is:

1. A pulling die comprising a hollow stand portion, a crown portion slidable vertically in the stand portion and having a depending bar fixed therein, said stand portion having a web extending across the interior thereof, a bearing 10 extending vertically from said web to receive said bar, a shaft in said web and extending outwardly from the stand, and cooperating means on said shaft and bar for vertically adjusting the 15 bar.

2. A pulling die comprising a hollow stand portion, a crown portion slidable vertically in the stand portion and having a depending bar fixed therein, said stand portion having a web extending across the interior thereof, a bearing extending vertically from said web to receive said bar, a shaft in said web and extending outwardly from the stand, and cooperating means on said shaft and bar for vertically adjusting the bar, said 20 cooperating means comprising gear teeth on said bar, and a gear on said shaft having teeth meshed with the teeth on said bar.

3. A pulling die comprising a hollow stand portion, a crown portion slidable vertically in the stand portion and having a depending bar fixed therein, said stand portion having a web extending across the interior thereof, a bearing extending vertically from said web to receive said bar, a shaft in said web and extending outwardly 30

from the stand, cooperating means on said shaft and bar for vertically adjusting the bar, and manually adjustable means for locking said bar against vertical movement in its bearing.

4. A pulling die comprising a hollow stand 5 portion, a crown portion slidable vertically in the stand portion and having a depending bar fixed therein, said stand portion having a web extending across the interior thereof, a bearing extending vertically from said web to receive 10 said bar, a shaft in said web and extending outwardly from the stand, cooperating means on said shaft and bar for vertically adjusting the bar, and manually adjustable means for locking said bar against vertical movement in its bearing, 15 said stand having an outwardly flaring brim receiving surface at the top thereof.

5. A pulling die comprising a hollow stand portion, a crown portion slidable vertically in the stand portion and having a depending bar 20 fixed therein, said stand portion having a web extending across the interior thereof, a bearing extending vertically from said web to receive said bar, a shaft in said web and extending outwardly from the stand, cooperating means on said shaft 25 and bar for vertically adjusting the bar, and manually adjustable means for locking said bar against vertical movement in its bearing, said stand having an outwardly flaring brim receiving surface at the top thereof, and said stand 30 having downwardly projecting leg portions integral therewith for supporting the stand.

ABRAHAM SOLOSKO.
